UNITED STATES PATENT OFFICE

PERLEY R. GLASS, OF SALEM, MASSACHUSETTS, ASSIGNEE TO UNITED SHOE MACHINERY CORPORATION, OF PATERSON, NEW JERSEY, A CORPORATION OF NEW JERSEY

FOLDING MACHINE

Original application filed September 28, 1928, Serial No. 309,020. Divided and this application filed February 9, 1932. Serial No. 591,871.

This invention relates to folding machines and is herein illustrated as embodied in a machine for folding the margins of the covers of cases in which books are bound, the present application being a division of application Serial No. 309,020, filed September 28, 1928.

In the manufacture of such cases it is customary to cement two boards to a cover of flexible material, such as leather or cloth, with 10 the margins of the cover projecting beyond the edges of the boards, and then to fold these projecting margins over upon the adjacent margins of the boards to form the case.

The corners of the cases may be round or 15 square, and the manner in which the parts of a case are cut and folded differs according to whether round corners or square corners are desired. Such cases, when finished, have four straight edges and four round corners; and

20 two types of machines for folding such cases have been proposed. In one type the four straight edges and the four round corners are folded at a single operation. In the other type the straight edges are presented one at a 25 time to a straight edge folding mechanism and the round corners are presented similarly to a round corner folding mechanism, the present invention being illustrated as embodied in a machine of the latter type.

30 The straight edge folding mechanism of machines of this type commonly comprises a work support and an edge guide so arranged that when the work is placed upon the support the margin of the cover is bent upright about 35 the edge of the adjacent board. After the work has been so placed, a reciprocating folder moves over the support to fold the margin of the cover over upon the margin of the board, and then the work support is raised 40 to press the fold against the under side of the folder.

According to one feature of the present invention there is provided a pivoted folder adapted to be swung about its pivotal axis 45 by an actuator to which it is connected by link mechanism. In the illustrated machine the folder is a normally upright flat bar, and the actuator is a reciprocating plate which swings the folder into a horizontal position and 50 moves over the folder so as to form a firm

backing or support for the folder when the work support is raised to press the fold against the under side of the folder. Such a construction, while adapted for all sizes of work, is particularly advantageous when 55 large book cases having long tops, bottoms and sides are being operated upon. The swinging folder bar folds the margin of the cover evenly over the board, and the actuator prevents the folder bar from springing when 60 the work support is moved up to press the fold against the under side of the folder bar.

This and other features of the invention, including certain details of construction and combinations of parts will be described as embodied in an illustrative machine and pointed 65 out in the appended claims.

Referring now to the accompanying drawing,

Fig. 1 is a perspective of a portion of a machine in which the present invention is embodied;

Fig. 2 is a perspective showing the mounting of the straight-edge folder; and

Figs. 3 and 4 are details principally in section showing the swinging straight-edge folder in two positions.

Before describing what is new, a brief description of what is old will be given. The machine, as has been explained, is designed 80 to fold the margins of covers of cases for books over the edges of the boards thereof and comprises straight-edge folding mechanism and round corner folding mechanism.

The work, which is the unfolded case of a 85 book, commonly comprises two boards, each of which has two rounded corners. The cover is of flexible sheet material such as leather, imitation leather or cloth. The boards may be of a thick and stiff material 90 such as cardboard or of a thin and comparatively flexible material such as paper. The work, as it comes to the machine, consists of the boards beyond the edges of which the margin of the cover projects; and two alternative methods of folding such a piece of work are commonly employed. Either the four straight edges are folded first up to 95 points adjacent to the round corners, and then the round corners are folded, or else 100

the round corners are folded first and then the straight edges. Either method may be carried out by the illustrated machine; but, for convenience, the machine will be described as used to fold the straight edges first and then the round corners.

The straight-edge folding mechanism comprises a flat work support or table 21 (Fig. 1) and a straight edge guide 23, the work 10 being placed upon the support in such a manner that the edge guide and the normally upright folder 25 bend up the margin of the cover substantially at right angles to the surface of the support; and, when power is applied to the machine, the folder folds the upstanding margin over upon the board or boards up to points adjacent to two of the rounded corners of the boards. The folder 25 of the illustrated machine is new; and 15 inasmuch as the purpose of the present introductory description is principally to point out what is old, it will be sufficient at this time to explain with respect to this folder that it is a pivoted plate which swings from the position shown in Fig. 3 to that shown in Fig. 4 to fold the upstanding margin of the cover 200 over upon the board 100. When 20 this has been done, the support 21 is raised to press the fold against the under face of the folder. The table or support 21 is mounted upon a vertically reciprocable cross head, not shown, which is raised at the proper time to press the fold. The parts of the machine 25 normally occupy the positions shown in Figs. 1 and 3 with the folder 25 upright and the support 21 in lowered position. The work 30 is placed upon the support, as shown in Fig. 3, and then power is applied to the machine whereupon the folder swings over into the 35 position shown in Fig. 4, the support rises to press the fold, and then the parts return to the positions shown in Fig. 3 ready for the presentation of a second piece of work.

The round corner folding mechanism will 40 be very briefly described, reference being made to application Serial No. 309,020 referred to above, in which it is disclosed in detail and claimed. This mechanism comprises a generally triangular work support 50 37 having a rounded nose. The corner of the book case is placed upon this support with the margin of the cover extending over an edge guide 41 which fits about two sides and the rounded end of the triangular work support 37. There is then brought down upon the work a forming plate 43 and a forming block 51. The work support and the work 55 upon it are thus pressed down a short distance whereby the margin of the cover is bent up into the horizontal path of movement of a folder 47 which has a generally V-shaped forward edge provided with a curved recess where would otherwise be the sharp apex of the V. The forming plate 43 and the forming block 51 are moved forward

until their curved ends are in register with the curved nose or end of the generally triangular work support 37, and the folder 47 is moved forward. The folder, during the first part of its movement, gathers the upstanding margin of the corner of the cover about the forming block and, during the second part of its movement, folds this margin over the forming plate 43, the forming block being pushed ahead by the folder. The forming plate 43 is withdrawn from beneath the folded over margin of the cover, and the work support 37 is pushed up to press the fold against the under face of the folder. The parts of the round-corner folding mechanism then return to their normal positions of rest ready to permit the unfolded corner of another book case to be presented to said mechanism. The folder 47 is fast to a folder carrier (not shown) to which is also fast 80 a plate 125 which reciprocates with the folder.

No further description of the round corner folding mechanism or of the mechanism for operating the round corner folding mechanism and the work support 21 will be given, reference being made to the parent application or to U. S. Letters Patent No. 1,776,390, granted September 23, 1930, upon an application filed in the names of Perley R. Glass and James E. McIntire. With regard to the patent it may be noted that in the machine there shown the plate, which bears the numeral 65 in Fig. 2 of the patent and corresponds to the plate 125 of the present application, is itself the reciprocating folder of the straight-edge folding mechanism, whereas, in the present machine, as will appear below, the plate 125 serves to actuate the swinging plate 25 which is the folder of the straight-edge folding mechanism of the present machine. It will be understood that in the present machine, as in the machine of the parent application and the machine of the patent, the two folding mechanisms, the round corner and the straight edge, are operated simultaneously once for each cycle of the machine, but that work is being folded in any given cycle by only one of the two folding mechanisms, the other being idle at the time.

Turning now to the new features, the swinging plate 25, which is the folder, is provided with two portions 228, 230 which project from the face of the plate and are the effective portions of the folder. It will be understood that the particular folder shown is adapted to fold the straight edges of a case of a particular size. A case is commonly oblong, the top and bottom edges being considerably longer than the side edges. In the operation of the machine, the straight edges along the sides of the case are presented to the shorter effective portion 228 of the folder and the straight edges along the top and bottom of the case 120 125 130

are presented to the longer effective portion 230.

The folder 25 is adapted to swing about the alined axes of pivot pins 128, 129 which are held stationary in bores formed in stationary lugs 130, 131 by set screws, one of said screws being shown at 133 in Fig. 2. These lugs are rigidly connected by a bar 139, the forward edge of which forms the edge guide 23 for the work. The swinging folder has fast to its ends arms 135, 137, the hubs of which are provided with bores to receive respectively the pins 128, 129. In Fig. 2, the arm 135 with one end of the folder 25 and the stationary lug 130 with part of the bar 139 are shown in spaced relation. In order to assemble the parts, the set screw 133 is loosened and the pin 128 pulled to the left, as shown; then the hub of the arm 135 is placed at the right of the lug 130, the pin 128 is pushed to the right so as to extend into the bore in the hub of the arm 135, and the set screw 133 tightened once more.

In order to actuate the folder 25, the arms 135, 137, to which it is fast, are swung about the common axis of the pivots 128, 129; and this swinging movement is imparted to the arms by the reciprocation of the actuator plate 125 which has been described above. Fast to opposite margins of the plate 125 are brackets 141, 143 to which links 145, 147 are pivoted respectively at 149, 151. The forward ends of these links 145, 147 are pivoted respectively at 153, 155 to the rear end of curved links 157, 159, the forward end of the curved link 157 being pivoted at 161 to the outer end of the arm 135, and the forward end of the curved link 159 being pivoted at 163 to the outer end of the arm 137. With this construction it will be clear that, when the plate 125 is moved forward (toward the left as viewed in Figs. 3 and 4) from the position shown in Fig. 3 to the position shown in Fig. 4, the folder 25 will be swung from its normal vertical position into the horizontal position shown in Fig. 4 and in this movement will fold the upstanding margin of the straight edge of the cover 200 (Fig. 3) down upon the board 100 (Fig. 4).

Inasmuch as the different pieces of work which are of substantially the same thickness may vary somewhat in that dimension, it is desirable to provide means for permitting the folder actuating mechanism to yield when occasion arises. To this end the levers 145, 147 are mounted for yielding movement. Referring to Figs. 3 and 4, the right-hand end of the lever 145 is received between a stop screw 165 and a spring-pressed plunger 167 both of which are mounted in extensions which are part of the bracket 141. Referring to Fig. 1, the right-hand end of the lever 147 is received between a stop screw 169 and a spring-pressed plunger like the spring-pressed plunger 167. The two levers 145,

147, mounted in this manner, are thus capable of being swung slightly in a clockwise direction (Figs. 3 and 4) about their pivots in opposition to the action of the spring-pressed plungers, if a particularly thick piece of work is being operated upon.

It should be particularly noted that, when the plate 125 has been moved into the position shown in Fig. 4, the forward portion of the plate rests upon the upper surface of the swinging folder 25 and serves as a firm backing for the folder against the upward thrust of the table 21, when that table is moved up to press the folder. It should also be noted that the axis about which the folder 25 swings (Fig. 3) coincides substantially with the upper corner of the edge gage 23.

In order to ensure that the margin of the work shall be evenly folded and the fold uniformly pressed irrespective of slight differences in thickness which may be present in the work, the work support 21 has a recess to receive a plate 173 (Fig. 1) of spring metal, the operative portion of said plate comprising a plurality of tongues as shown; and beneath this plate is a rubber pad 175.

Assuming that a folder 25, having portions 228 and 230 of the proper lengths for the book cases which are to be folded, has been mounted in the machine, the operation of the machine is as follows:—

One of the side edges of the case is placed upon the work support in proper relation to the portion 228 of the folder, and the machine is caused to operate, thereby folding the margin of the cover of the case along this straight edge up to points spaced somewhat from the two corners at that side of the case. This operation is then repeated on the other side edge. Next the two end edges are folded one after the other, making use of the portion 230 of the folder. The sides of the cover of the book case have now been folded except for small portions on both sides of the four corners of the case, and the corners of the cover are still unfolded. The corners of the cover and the adjacent unfolded portions of the sides of the cover are now folded in four separate operations, making use of the round corner folding mechanism.

Although the invention has been set forth as embodied in a particular machine, it should be understood that the invention is not limited in the scope of its application to the particular machine which has been shown and described.

Having thus described my invention, what I claim as new and desire to secure by Letters Patent of the United States is:

1. A machine of the class described having, in combination, a work support, a pivoted folder plate, an actuator for the folder plate, mechanism including a link for connecting the actuator with the folder plate, and means for operating the actuator.

2. A machine of the class described having, in combination, a work support, a pivoted folder plate, an actuator for the folder plate, yielding mechanism including a link for connecting the actuator with the folder plate, and means for reciprocating the actuator.
3. A machine of the class described having, in combination, a work support, a pivoted folder plate, an actuator for the folder plate, mechanism including a link for connecting the actuator with the folder plate, and means for reciprocating the actuator.
4. A machine of the class described having, in combination, a work support, a pivoted folder in the form of an elongated plate, arms rigid with the folder, an actuator for the folder, connections between the actuator and the arms, and means for operating the actuator.
5. A machine of the class described having, in combination, a work support, a pivoted folder in the form of an elongated plate, arms rigid with the folder, an actuator for the folder, connections between the actuator and the arms, and means for reciprocating the actuator.
6. A machine of the class described having, in combination, a work support, an edge guide to facilitate bending the margin of the work upward, a pivoted folder, an actuator for the folder, mechanism connecting the actuator with the folder whereby movement of the actuator swings the folder about its pivot, means for moving the actuator to cause the folder to bend the upstanding margin of the work over upon the body portion of the work to form the fold and to cause a portion of the actuator to be positioned above the folder, and means for raising the work support to press the fold against the under face of the folder while the folder is backed up, as described, by the actuator.
7. A machine of the class described having, in combination, a work support, a pivoted folder, an actuator for the folder, mechanism connecting the actuator with the folder whereby movement of the actuator swings the folder about its pivot, and means for moving the actuator to swing the folder over upon the work and to cause the actuator to contact with that face of the folder opposite the one which is in contact with the work.
8. Mechanism for folding the margins of the cover of a book case over the straight edges of the boards thereof having, in combination, a work support, a pivoted folder plate, an actuator for the folder plate, mechanism including a link for connecting the actuator with the folder plate, and means for reciprocating the actuator.
9. Mechanism for folding the margins of the cover of a book case over the straight edges of the boards thereof having, in combination, a work support, a pivoted folder

plate, an actuator for the folder plate, yielding mechanism for connecting the actuator with the folder plate, and means for reciprocating the actuator.

10. A machine of the class described having, in combination, a work support, a swinging folder provided with a plurality of spaced effective portions, one adapted to operate upon the top and bottom margin of the cover of a case for a book and another upon the side margins, and means for swinging the folder over upon the work.

11. A machine of the class described having, in combination, a work support, a folder provided with spaced effective portions in the path of movement of a selected one of which a selected portion of the cover of a book case may be presented, and means for actuating said folder to fold the margin along one edge of the case from a point adjacent to one corner of the case to a point adjacent to another corner, leaving the corner portions unfolded.

12. A machine of the class described having, in combination, a work support, a pivoted folder provided with spaced effective portions in the path of movement of a selected one of which a selected portion of the cover of a book case may be presented, and means for swinging said folder to fold the margin along one edge of the case from a point adjacent to one corner of the case to a point adjacent to another corner, leaving the corner portions unfolded.

In testimony whereof I have signed my name to this specification.

PERLEY R. GLASS.
